UNITED STATES PATENT OFFICE

2,634,819

AUTOMATIC VACUUM CLEANER

George H. Cranmer, Philadelphia, Pa., assignor
to Electrolux Corporation, Old Greenwich,
Conn., a corporation of Connecticut

Application September 21, 1949, Serial No. 117,040

13 Claims. (Cl. 183—37)

1

This invention relates to a vacuum or suction type cleaner adapted to dispose of the dirt accumulated therein. More particularly, it embraces an automatically conditioned tank type cleaner having mechanically actuated self-contained control mechanisms for removing accumulated dirt after such an amount is collected in a porous disposable bag located within the cleaner as is capable of effecting a predetermined change in the operating efficiency of the cleaner.

It is a major object of this invention to provide an improved vacuum cleaner having automatic means for disposing of dust collected in a paper bag by ejecting from the cleaner the porous disposable paper bag filled with dust separated from the suction air stream, the ejection of the dust and dirt filled bag being effected upon the attainment of a predetermined pressure drop within the cleaner.

It is a further and important object hereof to provide completely mechanical means for effecting the automatic operation of the dust bag ejecting devices.

A still further object is to provide a vacuum cleaner having a large dust collecting capacity which is effected at a substantially uniform efficiency.

A further object of this invention is to provide a device which avoids the inconveniences present in all cleaning devices wherein a dust loaded bag is used and periodically necessitates occasional removal or replacement in order to maintain efficient operation and whereby considerable difficulty and discomfiture has been heretofore experienced by the operator in the removal of such a bag and the accumulated dust and dirt therein.

Still other and further objects will be disclosed hereinbelow or will be obvious to those skilled in the art from a study of the following description together with the appended drawings wherein:

Figure 1 is a partial vertical sectional view taken lengthwise through a vacuum cleaner embodying the features of this invention;

Figure 2 is a partial horizontal sectional view of the cleaner shown in Fig. 1 showing additional details of structure;

Figure 3 is an end view of the cleaner with the cover open;

Figure 4 is a partial vertical sectional view taken on the line 4—4 of Fig. 3 and showing the bag ejection tray in completely extended position, the bag having been ejected from the cleaner casing;

Figure 5 is a partial perspective view, with

portions broken away, showing detailed arrangements of the various parts in their cooperative relationship;

Figure 6 is a perspective view of the surge arresting momentum or gravity actuated element shown in position in Fig. 5 pivoted on and adapted to move with the main pressure plate; and

Figure 7 is a perspective view of the front cover latching mechanism and circuit breaking device with portions of the cover plate therefor broken away to show the parts more clearly.

It is a feature of this invention that the entire operation of the cleaner in its dust disposal capacity is automatic, self-contained and after being once initiated by the establishment of predetermined changes in the operational characteristics of the air suction stream within the cleaner, the entire sequence of operations terminating in the ejection of the dust-filled bag is effected mechanically. Thus, upon a predetermined pressure difference being built up within the cleaner between the inside and the outside of the dust-filled bag which exerts a continuous progressively increasing force upon a pressure plate, a series or sequence of spring actuated steps is initiated resulting finally in the ejection of the dust-filled bag from the cleaner casing. In a preferred embodiment, the pressure plate upon gradual actuation finally releases the cover of the cleaner; this in turn breaks a circuit cutting off the power supply to the motor fan unit and after a predetermined drop in the air suction current a second or auxiliary pressure plate releases the bag ejector tray, thereby ejecting the dust-filled bag from the cleaner casing and out upon the floor.

In accordance with a preferred embodiment of this invention, the automatic dust bag ejection unit is spring actuated and its operation is effected by a tripping mechanism utilizing the pressure exerted by the bag to initiate the tripping step. This bag pressure is caused by a pressure difference built up within the cleaner casing and more particularly between the inside and outside of the dust-collecting bag, progressively increasing during the dust collecting process. A pressure plate initiating the sequence of steps culminating in bag ejection is operated by the dust bag surface which exerts more and more force against the plate, the pressure increasing with continued dust collection. The force exerted thus progressively increases, and subsequently attains sufficient strength to release the cover restraining latch mechanism 60.

Fig. 7, pivoted at 61 and biased by spring 64 for holding the cover closed. The release of the cover first breaks a circuit at contact points 62 through release of plunger 63 which is spring biased to the left, Fig. 7. This deenergizes the motor fan unit. Thereafter the front cover continues to open and after opening a full 90°, another trigger mechanism (described below) for finally releasing the bag ejector tray is tripped, allowing the bag ejector tray to push the bag outward and eject the bag and its contained dirt from the cleaner casing.

The ejector tray 82, Figs. 1, 2, 4 and 5, moves outward when finally released until it strikes a stop 150 in the forepart of the dust bag carrying sleeve 20. The momentum of the moving dust-filled bag 22 causes it to continue on out of the cleaner after which it lands on the floor.

Referring now more particularly to the drawings, vacuum cleaner housing 10, Fig. 1, is a hollow casing having a handle 11 and appropriately supported on a pair of runners 12. The suction or inlet portion of the casing 10 is provided with a conventional air inlet or suction nozzle which is connected by a suitable wand and flexible hose (none of which are shown) to connecting coupling 13 of a movable cover 14 biased to open position by spring 15 and hinged at 16, Fig. 2, to form an air tight seal with the casing 10 through reinforcing body ring member 18 and conventional sealing rings 28. Switch member 17, Figs. 1 and 2, provides the on and off manual control for the cleaner unit.

A perforated sleeve 20 for holding a dust bag 22 (of disposable paper or cloth construction) is slidably fitted and affixed within the cleaner housing 10. In the embodiment shown, the sleeve 20 is substantially rectangular in cross-section, Fig. 3, and is thus adapted to take a long dust bag of substantially similar square-shaped cross-section.

The dust bag 22, Fig. 1, comprises a container of paper or similarly air pervious, dust impervious, material 24 affixed at its mouth to the rear surface of a hard paper or cardboard disc 26, the latter of which is clamped between cover 14 and the end of cylinder 10 with the aid of suitable sealing rings 28, Fig. 3. Cardboard disc 26 has a central opening 30 through which the inner end of tubular member 32 protrudes in order to introduce the air and entrained dust directly into the inside of dust bag 24.

The entire surface of sleeve housing 20 is provided with perforations 21, Fig. 4, in order to allow dust free air to pass therethrough and into chamber 40, the air then passing to spring compression compartment 42 and then to motor fan compartment 44 which contains mounted therein fan 46 and motor 48. The fan is provided with an air inlet 50 through which the air passes to the housing of motor 48 and out through an axial opening in end cap 52.

A perforated supporting partition 70 extending from and supported by the cleaner housing 10 has lugs 72 mounted thereon for supporting and holding one end of a spiral compression ejecting spring 74. The other end of the compression spring is shown as fitting into lugs 80 mounted on the rear of an ejector tray 82 including a sleeve which is adapted to slide smoothly within sleeve housing 20. The length of the sliding contact between the sleeve of ejector tray 82 and the inside of cylindrical sleeve casing 20 is sufficient to prevent seizing and binding between their contacting surfaces.

Ejector tray 82 is held in spring compressing position by the engagement of a lug 100, Fig. 2, and Fig. 5 thereon with an opening 101, Fig. 2, in the surface of main pressure plate 102 and substantially at the spring biased or right-hand end thereof. Pressure plate 102 moves freely in a cut-out section 83, Figs. 3 and 5, of tray 82 and is pivoted at 104, Fig. 2, to the side of sleeve housing 20, being held or biased towards the central axis of the sleeve casing by springs, such as 106. Thus, upon pushing the tray 82 to the extreme right, Fig. 5, it finally locks into ejector spring compressing position as shown in Fig. 1 and Fig. 2. This position facilitates the insertion of the disposable paper dust bag.

This position is maintained after the closure of cover 14 whereupon the cover, contacting plunger 110, Fig. 1 and Fig. 5, causes inclined plane 111 to lift the left end of lever 112 causing the depending right end of lever 112 to enter opening 120 in sleeve 20 and then pass through opening 121 in the sleeve of ejector tray 82. In this position lever 112 is locked in ejector plate restraining position by the engagement of the right depending end of lever 112 with the upper bent free end of auxiliary pressure plate 130. Auxiliary pressure plate 130 is fulcrumed at 131 to the inner surface of tray 82.

Auxiliary pressure plate 130, Fig. 1, is biased 30 by leaf spring 132 to forward position away from the ejector tray surface 82 thus releasing the depending right end of lever 112. The biasing spring 132, Fig. 1, is of such predetermined strength as to be maintained in compressed condition by the cooperative action of the end of the dust bag and the air suction current coursing therethrough when the vacuum cleaner is operating under normal dust collecting conditions. Thus even when cover 14 opens and releases pin 110, the auxiliary pressure plate 130 maintains ejection tray restraining lever 112 in locked condition at its depending right hand end until the air suction produced by the motor fan unit diminishes because the deenergization of the motor fan unit accompanying the breaking of contact 62, Fig. 7, decreases the air suction stream so as to be no longer capable of holding plate 130 against the contrary biasing action of spring 132. The air suction progressively decreases when the motor fan unit is thus deenergized, i. e. the release of cover closure 61 effects a substantial simultaneous opening of circuit breaking switch 62. Such a delayed release of the sleeve of ejector tray 82 makes possible the utilization of all the energy stored in the compressed ejecting spring 74 without any checking or loss of ejecting force due to the counteracting suction of counter-current air passing through the dust bag and cleaner casing.

The cleaner is loaded with a clean bag by first pushing the sleeve of ejecting tray 82 back into its sleeve housing until lug 100 engages opening 101, Fig. 2 (see also Fig. 5) in the surface of pressure plate 102. The dust collecting bag is then inserted with the bag portion in the sleeve housing 20 and the cardboard disc lying within body ring 18, Fig. 3. When the cover 14 is then closed and the vacuum cleaner is first operated and dust collected, the building up of a predetermined pressure within the bag and against main pressure plate 102 causes main pressure plate 102 to release lug 100 on tray 82, whereupon tray 82 moves forward slightly so as to be free from all restraints except that of the depending right hand end of lever 112, Fig. 1 and Fig. 5.

Then further collection of dust and dirt builds

up a greater and greater pressure difference within the cleaner casing and between the inside and outside of the dust bag. This results in the dust collecting paper bag 22 exerting greater and greater pressure on pressure plate 102, Fig. 2. 5 If a sudden surge or gust of air enters the dust bag as is occasioned by the sudden lifting of the dust collecting nozzle and wand off a carpet being cleaned and on to the bare floor, the sudden movement of pressure plate 102 is arrested by movable weighted dog 160, Figs. 2 and 6, pivoted at 161 (see Fig. 6) on pressure plate 102 moving straight out and because of its momentum remaining in its upward position and abutting against fixed ledge 162. Thus cover tripping pin 140, Figs. 2 and 5 is kept from contacting button 141 on lever arm 143 and releasing the cover latch 60 on cover 14 whenever a sudden surge or 10 gust of air passes through the cleaner dust bag 22.

However, when the pressure difference within the cleaner casing and between the inside and outside of the dust collecting bag builds up slowly, movable arm 160 under the action of gravity then slides down the inclined plane 163 and passes on through opening 164 with one continuous motion, 25 and pin 140 is then free to contact button 141 to release cover latch 60. The release of cover latch 60, Fig. 7 which is spring biased to move outwardly by spring 64, also releases plunger 63 which is in turn spring biased to move to the left and cause circuit breaking switch 65 to break the motor fan energizing circuit at contacts 62. Then the release of spring biased cover 14 leaves 30 cover 14 free to swing wide open. This allows plunger 110, which is spring biased to the left, Figs. 1 and 5, to release the left end of lever arm 112 which is then triggered or conditioned for release by the pressure exerted by biasing spring 132 against auxiliary pressure plate 130.

The ejector tray 82 is held in spring compressing position until the depending right hand end of lever 112 is itself released by the slowing down of the deenergized motor fan unit which causes auxiliary pressure plate 130, Fig. 5, to move to the left and release the locked depending end of lever 112. Lever 112 which is spring biased to move counter-clockwise then releases ejector tray 82 which is forced forward in its sleeve 20 by compressed ejector spring 74. Ejector tray 82 is halted by limit stops 150, Fig. 4. The dust filled bag, pushed by tray 82, gathers momentum in its outward travel and having nothing to impede its progress is ejected out through the opening left in the casing by the outward swinging of cover 14 and is deposited on the floor.

It is to be understood that the embodiment herein specifically described is merely illustrative of the general principles involved in this invention and that the invention is to be limited solely by the scope of the appended claims.

What I claim is:

1. In a vacuum cleaner, the combination comprising a casing having an opening, a movable cover for said opening, releasable means for holding said cover in closed position, means for producing a flow of air through said casing, a dust bag in said casing in the path of said air flow for separating entrained dirt from said air, means responsive to pressure exerted by said dust bag for releasing said cover holding means, mechanical means for arresting the operation of said pressure responsive means upon the production of a surge of air flow through said casing, releasable means for ejecting said dust bag, and auxiliary delayed response means conditioned for op-

eration upon the opening of said cover for delaying the release of said dust bag ejecting means.

2. In a vacuum cleaner, the combination comprising a casing having an opening, a movable cover for said opening, releasable means for holding said cover in closed position, means for producing a flow of air through said casing, a dust bag in said casing in the path of said air flow for separating entrained dirt from said air, principal means responsive to pressure exerted by said dust bag for releasing said cover holding means, releasable means for ejecting said dust bag, means responsive to the opening of said cover for conditioning said bag ejecting means for release, switching means responsive to the opening of said cover for deenergizing the air flow producing means, and auxiliary means responsive to pressure exerted by said dust bag for delaying the release of said bag ejecting means until the pressure exerted by said dust bag attains a predetermined minimum whereby the bag ejecting means is capable of more effective ejection of the dust bag.

3. In a vacuum cleaner, the combination comprising a casing having an opening, a movable cover for said opening, releasable means for holding said cover in closed position, means for producing a flow of air through said casing, a dust bag in said casing in the path of said air flow for separating entrained dirt from said air, principal means responsive to pressure exerted by said dust bag for releasing said cover holding means, releasable means for ejecting said dust bag, means responsive to the opening of said cover for conditioning said bag ejecting means for release, switching means responsive to the opening of said cover for deenergizing the air flow producing means, auxiliary means responsive to pressure exerted by said dust bag for delaying the release of said bag ejecting means until the pressure exerted by said dust bag attains a predetermined minimum whereby the bag ejecting means is capable of more effective ejection of the dust bag, and means operated by said principal pressure responsive means for arresting the operation of said pressure responsive means upon the production of a surge of air flow through said casing.

4. In a vacuum cleaner, the combination comprising a casing having an opening, a movable cover for said opening, releasable latching means for holding said cover in closed position, means for producing a flow of air through said casing, a dust bag in said casing in the path of said air flow for separating entrained dirt from said air, a main pressure plate disposed laterally in said casing and movable by pressure exerted thereagainst by said bag for releasing said cover holding means, releasable means for ejecting said dust bag, means responsive to the opening of said cover for conditioning said bag ejecting means for release, switching means responsive to the opening of said cover for deenergizing the air flow producing means, and an auxiliary pressure plate adjacent the end of said bag in said casing and movable by pressure exerted by said dust bag for delaying the release of said bag ejecting means until the pressure exerted by said dust bag attains a predetermined minimum whereby the bag ejecting means is capable of more effective ejection of the dust bag.

5. In a vacuum cleaner, the combination comprising a casing having an opening, a movable cover for said opening, releasable latching means for holding said cover in closed position, means for producing a flow of air through said casing, a dust bag in said casing in the path of said air

flow for separating entrained dirt from said air, primary means responsive to pressure exerted by said dust bag for releasing said cover holding means, releasable means for ejecting said dust bag, means responsive to the opening of said cover for conditioning said bag ejecting means for release, switching means responsive to the opening of said cover for deenergizing the air flow producing means, auxiliary means responsive to pressure exerted by said dust bag for delaying the release of said bag ejecting means until the pressure exerted by said dust bag attains a predetermined minimum whereby the bag ejecting means is capable of more effective ejection of the dust bag, and a pivoted dog member movable horizontally and operated by said primary pressure responsive means, an inclined plane surface over which said dog member is adapted to slide, an abutment for arresting the movement of the dog member when the acceleration of the dog member is greater than the force of gravity tending to cause it to ride on the inclined plane surface for arresting the operation of said pressure responsive means as a result of a surge of air flow through said casing.

6. In a vacuum cleaner the combination comprising having an opening, a movable cover for said opening, releasable means for holding said cover in closed position, means for producing a flow of air through said casing, a dust bag in said casing in the path of said air flow for separating entrained dirt from said air and insertable into and removable from said casing through said opening, mechanical means operable to move said dust bag outwardly through said opening, means responsive to a predetermined pressure exerted by said dust bag for releasing said dust bag moving means for a predetermined portion of its outward travel, means responsive to the application of an additional predetermined pressure by said dust bag beyond said first mentioned pressure for operating said cover releasing means, and means responsive to the opening of said cover for conditioning the means for moving said bag outwardly from said casing through said opening for operation.

7. In a vacuum cleaner, the combination comprising a casing having an opening, a movable cover for said opening, releasable means for holding said cover in closed position, means for producing a flow of air through said casing, a dust bag in said casing in the path of said air flow for separating entrained dirt from said air, means responsive to pressure exerted by said dust bag for releasing said cover holding means, releasable means for ejecting said dust bag, means responsive to the opening of said cover for conditioning said bag ejecting means for release, and a pivoted dog member movable horizontally and operated by said pressure responsive means, an inclined plane surface over which said dog member is adapted to slide, an abutment for arresting the movement of the dog member when the acceleration of the dog member is greater than the force of gravity tending to cause it to ride on the inclined plane surface for arresting the operation of said pressure responsive means as a result of a surge of air flow through said casing.

8. In a vacuum cleaner, a casing having an opening, a movable cover for said opening, means for producing flow of air through said casing, a dust separating container in said casing in the path of air flow therethrough, spring biased means for ejecting said container from said casing through said opening, first latching means

for retaining said ejecting means in fully retracted position, means responsive to pressure drop through said container for releasing said first latching means and for opening said cover, 5 second latching means for arresting movement of said ejecting means after the latter has been released by said first latching means, and means responsive to opening of said cover for releasing said second latching means.

9. In a vacuum cleaner, a casing having an opening, a movable cover for said opening, means for producing flow of air through said casing, a dust separating container in said casing in the path of air flow therethrough, spring biased means for ejecting said container from said casing through said opening, first latching means for retaining said ejecting means in fully retracted position, means responsive to pressure drop through said container for releasing said 15 first latching means, second latching means for arresting movement of said ejecting means after the latter has been released by said first latching means, means responsive to a greater pressure drop through said container for opening said cover, and means responsive to opening of said cover for conditioning said second latching means for release.

10. In a vacuum cleaner, a casing having an opening, a movable cover for said opening, means 30 for producing flow of air through said casing, a dust separating container in said casing in the path of air flow therethrough, spring biased means for ejecting said container from said casing through said opening, first latching means for retaining said ejecting means in fully retracted position, means responsive to increasing pressure drop through said container for releasing said first latching means and for opening said cover, second latching means for arresting movement of said ejecting means after the latter has been released by said first latching means, means responsive to opening of said cover for conditioning said second latching means for release, and means responsive to decreasing pressure drop through said container for completing the release of said second latching means.

11. In a vacuum cleaner, a casing having an opening, a movable cover for said opening, means for producing flow of air through said casing, a dust separating container in said casing in the path of air flow therethrough, spring biased means for ejecting said container from said casing through said opening, first latching means for retaining said ejecting means in fully retracted position, means responsive to increasing pressure drop through said container for releasing said first latching means, second latching means for arresting movement of said ejecting means after the latter has been released by said first latching means, means responsive to a greater pressure drop through said container for opening said cover, means responsive to opening of said cover for conditioning said second latching means for release, and means responsive to decreasing pressure drop through said container for completing the release of said second latching means.

12. In a vacuum cleaner, a casing having an opening, a movable cover for said opening, an electric motor, a fan driven by said motor for producing flow of air through said casing, means for supplying current to said motor, a dust separating container in said casing in the path of air flow therethrough, spring biased means for ejecting said container from said casing through said opening, first latching means for retaining

said ejecting means in fully retracted position, means responsive to pressure drop through said container for releasing said first latching means and for opening said cover, second latching means for arresting movement of said ejecting means after the latter has been released by said first latching means, and means responsive to opening of said cover for interrupting the supply of current to said motor and for releasing said second latching means.

13. In a vacuum cleaner, a casing having an opening, a movable cover for said opening, an electric motor, a fan driven by said motor for producing flow of air through said casing, means for supplying current to said motor, a dust separating container in said casing in the path of air flow therethrough, spring biased means for ejecting said container from said casing through said opening, first latching means for retaining said ejecting means in fully retracted posi- 20

tion, means responsive to increasing pressure drop through said container for releasing said first latching means and for opening said cover, second latching means for arresting movement of said ejecting means after the latter has been released by said first latching means, and means responsive to opening of said cover for conditioning said second latching means for release and for interrupting the supply of current to said motor, and means responsive to decreasing pressure drop through said container for completing the release of said second latching means.

GEORGE H. CRANMER.
